GARMENT SUPPORTER

Alfred D. Quasso, San Antonio, Tex., assignor of
one-fourth to Stephen Paul Daily, Jr., New
York, N. Y.

Application August 6, 1934, Serial No. 738,696

3 Claims. (Cl. 24—73)

This invention relates to garment supporters the purpose of which is to suspend the trousers or lower garment by means of a device of my invention by attaching same to the lower portion 5 of a shirt or other upper garment.

It is the primary object of my invention to provide a garment supporter with which the trousers of the wearer may be suitably supported by conveniently attaching same to the 10 tail of the outer shirt, and also to thus hold the shirt securely in place preventing it from slipping outside the trouser waistband.

A further object of my invention is to provide a device of the character described which may 15 be permanently sewed onto the inner waistband of the trousers or may be detachably affixed by a unique double safety pin of my invention.

A further object of my invention is to provide a garment supporter in which is incorporated 20 improved means by which the shirt may be doubly gripped to insure against its slipping out of engagement.

The invention will be fully and comprehensively understood from a consideration of the 25 following detailed description when read in connection with the accompanying drawing which forms part of the application, with the understanding, however, that the improvement is capable of extended application and is not confined to the exact showing of the drawing nor to the precise construction described and, therefore, such changes and modifications may be 30 made therein as do not affect the spirit of the invention nor exceed the scope thereof as expressed in the appended claims.

In the drawing:

Fig. 1 is an elevational view illustrating the 35 use of my garment supporter attached to the trouser waist band of the wearer.

Fig. 2 is a detail elevational view of my garment supporter illustrating its double attachment to the tail of the shirt.

Fig. 3 is a vertical central sectional view of Fig. 2; and

Fig. 4 is a perspective view of my device with the shirt attaching means opened out to illustrate the construction thereof.

In describing the invention in detail and the particular physical embodiment illustrating the invention, reference is had to the accompanying drawing wherein like characters of reference designate corresponding parts thruout the several views.

My invention comprises in general two component parts, that is, a plate indicated by

numeral 5 upon which is incorporated means for permanently attaching same to the inner waist band of a trousers and other means by which the plate 5 may be detachably affixed to the waist band, and a flexible tongue secured to the plate 5 by which, in cooperation with plate 5, my device may be attached to the tail of the shirt. Plate 5 is provided at its outer edges with a plurality of eyelets 6 by which same may be sewed onto the inner waist band of the trousers. 5 At the lower edge of plate 5 is hingedly attached a U-shaped double pointed safety pin 7, the hinge portion being formed by lugs 8 integral with plate 5 being bent over the intermediate portion of the safety pin 7. Plate 5 is further 10 provided with a symmetrical aperture 9, the upper portion of which has its edges converging 15 slightly to form a loop 10.

The portion of my device by which its attachment to the shirt tail is effected, comprises 20 a flexible tongue 11, an end of which is secured to the lower portion of plate 5 by a wire staple 12. A member 13, formed by punching a portion of the aperture 9, is bent back into parallelism 25 with the face of plate 5 to form a portion of the hinge of the safety pin 7 as well as to conceal the sharp ends of the wire staple 12, thus forming a neat practical structure at this portion of plate 5. Flexible tongue 11 is provided 30 at its free end with an overlapping member 14 upon the surface of which is integrally formed a button or stud 15. The position of the stud 15 is such that it may be engaged into loop 10 35 to grasp the tail of the shirt in cooperation with plate 5. Member 14 has its end arcuately formed 40 in parallelism with which an arcuate bead 16 is provided on one surface of flexible tongue 11. The bead 16 functions in cooperation with the arcuate free end of the member 14 to assist in holding the button 15 in engagement within the 45 loop 10, thereby effecting a more secure grasp of the garment by the associated members. This function of the bead 16 is more obvious in the illustration of the device as shown in Fig. 3. It is to be noted therein that the garment 45 is doubled under the overlapping member 14 and is thus engaged between the free end of member 14 and the bead 16, which bead by virtue of its proximity to the free end of member 14 effects the more secure holding of the latter 50 after the garment has been grasped by the device.

As hereinbefore stated, the plate 5 may be permanently attached by sewing onto the inner waistband of the trousers or, if desired, may be 55

detachably affixed to same by the insertion of the double safety pin 7. To insure protection of the pointed ends of safety pin 7 ears 17 are provided under which the points of the pin 7 may be hooked. In describing the attachment of my device to the tail of the shirt particular reference is directed to Figs. 2 and 3. The plate 5 has been previously attached to the trousers and flexible tongue 11 is held in position, as shown in Fig. 4, whence a portion of the tail of the shirt is doubled under the overlapping member 14. At this time the stud 15, being covered by the shirt tail, is inserted into loop 10 by slightly flexing tongue 11, which is of sufficient resilience to permit the convenient placement of button 15 within the loop and yet by its semi-rigidity to auxiliately the retention of button 15 in cooperation with the convergent edges of loop 10. It is to be observed that by the engagement of the shirt under the overlapping member 14 in cooperation with the arcuate bead 16 and the engagement of stud 15 in loop 10 effects a doubly secure gripping of the shirt, thus eliminating all possibility of accidentally releasing same.

What is claimed as new is:

1. A device of the character described comprising a first member adapted to be attached to a trousers, a second member hingedly attached to the lower end of the first member and including a flap at its upper end bent over toward the first member, the latter having a

slot and the flap being provided with a button adapted to be held in said slot, said second member including a bead just below the end of said flap and on the same side of the second member, said bead and said flap being so related as to grip a portion of a garment when said button is engaged in said slot.

2. A device of the character described comprising a first member adapted to be attached to a trousers, a second member hingedly attached to the lower end of the first member and including a flap at its upper end bent over toward the first member, the latter having a slot and the flap being provided with a button adapted to be held in said slot, a U-shaped pin pointed at its ends and hingedly attached to said first member and means extending from said first member and functioning as holding means and guards for the pointed ends of the pin.

3. A device of the character described comprising a first member adapted to be attached to a trousers, a second member hingedly attached to the lower end of the first member, the latter having a slot and the second member being provided with a button adapted to engage with said slot and a U-shaped pin pointed at its ends and hingedly attached to said first member and means extending from said first member and functioning as holding means and guards for the pointed ends of the pin.

ALFRED D. QUASSO.
